UNITED STATES PATENT OFFICE.

NICHOLAS ZUCK, OF ROCHESTER, NEW YORK.

GARMENT CONSTRUCTION.

Application filed July 21, 1921. Serial No. 486,408.

My invention relates to a garment construction, and has for its purpose to afford a method of securing the free edges of haircloth in a garment so as to prevent the hairs 5 from coming loose and working through the outer cloth of the garment.

A further object of the invention is to afford an arrangement for a garment that can be readily manufactured at a reasonable 10 cost, and which effectually retains the hairs of haircloth fabric and prevents their ends from protruding through the garment, thus increasing the efficiency and durability of a coat or similar structure.

Other objects of the invention will be apparent from the following description, in conjunction with the accompanying drawings, the novel features being pointed out 15 in the claim following the description.

20 In the drawing:

Figure 1 is a front elevation of a coat front, showing one application of my invention;

Figure 2 is a similar view of a modified 25 form of coat front, with the invention applied;

Figure 3 is a sectional view on line 3—3 of Figure 1, and

Figure 4 is a sectional view on line 4—4 30 of Figure 2.

The invention may be carried out in various ways, and resides essentially in applying a strip of protective fabric, such as a tape for instance, along a seam where haircloth is cut or along a free edge of haircloth, preferably with a layer of cement applied between the tape and the surface 35 to which it is attached, the result being both to firmly retain the ends of the hairs and 40 also to afford a barrier in the path of any hairs that might have a tendency to become loose.

In the form disclosed in Figures 1 and 3, the protective fabric is attached against the 45 surface of a layer of cotton or padding that overlies the haircloth, whereas in Figures 2 and 4, the protective fabric is secured directly against the haircloth, and between it and the overlying layer of padding.

50 Referring to Figures 1 and 3, 1 designates the main coat front support consisting of canvas, to which is attached the haircloth 2, while 3 designates the lapel portion, preferably formed of a more pliable haircloth or similar fabric and extending to a 55 point adjacent to the main haircloth por-

tion 2, said parts being secured to the canvas 1 and located adjacent to each other along the seam 4, while 5 designates the padding which overlies the haircloth portion 2 and 60 extends to the line of the seam 4.

Attached preferably to the padding 5 along the free edge of the haircloth is a strip of protective fabric 6, which may be in the form of a tape, preferably gummed, and attached to the structure by stitching. By using a gummed tape, a simple and comparatively inexpensive method is afforded for rigidly retaining the hairs, since when the garment is pressed in its final stages, the 70 heat of the pressing iron causes the gummed tape to adhere closely and provides a layer of cement, as it were, under the protective tape and in such position as to unite the free ends of the hairs more or less into one 75 mass, although other means may be employed for arranging a layer of cement between the strip of protective fabric and the free edge of the haircloth.

7 designate strips of similar protective 80 fabric or tape which are secured to the padding wherever the latter is cut or seamed, that is to say, wherever a cut is made through the haircloth and a free edge of the haircloth thereby exposed. The protective 85 fabric or tape is located over such seam or cut and affords a mechanical barrier against the ends of the hairs, and this combined with the retaining action of the cement serves effectively to maintain the hairs 90 against movement and to prevent them from protruding through the outer cloth of a garment.

In Figures 2 and 4, 8 designates the canvas portion, 9 is the haircloth, and 10 is the 95 cotton padding. In this instance, the protective fabric 11 is arranged between the cotton padding 10 and the haircloth 9, and is positioned before the cotton padding 10 is attached. Otherwise the method of attachment and functioning of the protective fabric is the same as that already described, a gummed tape being preferably employed and arranged with the gummed side against the haircloth so that when heat and pressure 100 are applied to the garment, a cementing action of the ends of the hairs takes place and the protective fabric is caused to adhere as closely as possible to the haircloth.

With both forms of the invention, the protective fabric is preferably secured in place 110 initially by stitching, this being conven-

iently done at the same time that the usual stitching operations are performed on the coat front; although other methods of attaching the protective fabric may be adopted, and the layer of cement under the protective fabric may be applied and caused to unite the hairs in other ways than that which I have described.

I claim:

10. A laminated fabric structure including a thickness of haircloth, a strip of protective tape stitched to said laminated structure,

said tape being located along the free edge of the haircloth and extending in opposite directions from said free edge and above the 15 plane of the haircloth, and a cementitious substance on the under surface of the tape toward the haircloth acting to form a close bond with the tape and to prevent the ends of the hairs in the haircloth from protruding. 20

In witness whereof, I have hereunto signed my name.

NICHOLAS ZUCK.
